DOLL

Eleanor Spann Lee, Chicago, Ill.

Application January 15, 1949, Serial No. 244

Term of patent 14 years

(Cl. D34—4)

To all whom it may concern:

Be it known that I, Eleanor Spann Lee, a citizen of the United States and a resident of Chicago, in the county of Cook and State of Illinois, have invented a new, original, and ornamental Design for a Doll, of which the following is a specification, reference being had to the accompanying drawing, forming a part thereof.

Fig. 1 is a front view of a doll showing my new design.

Fig. 2 is a sectional view of the doll on line 2—2 in Fig. 1.

I claim:

The ornamental design for a doll, as shown.

ELEANOR SPANN LEE.
